UNITED STATES PATENT OFFICE.

HORACE E. BOUCHER, OF NEW YORK, N. Y.

SPRING MOTOR.

Application filed January 31, 1922. Serial No. 532,949.

My invention relates to spring operated motors. It relates particularly to a compact, artistic spring motor adapted to operate light-running devices such as toy boats, toy submarines, toy aeroplanes, toy automobiles and so forth.

The object of the invention is to provide a spring-controlled motor which shall be easily, economically and rapidly constructed, and which, while efficient in operation, shall be of few parts, easily put together and easily demounted, all parts being interchangeable, so the parts may upset and be rapidly clinched together, and, in addition to its constructive and operative advantages, presenting an artistic and popular appearance. In particular and in accordance with my invention, the parts are so constructed as to present the outward appearance of a one cylinder gasoline engine.

The drawings accompanying and forming part of the present specification show one embodiment of the invention whose exterior resembles a one-cylinder gasoline engine. In these drawings:

Figure 1 shows a side elevation;

Fig. 2 is a front elevation;

Fig. 3 is a top view of the assembled motor;

Fig. 4 shows a plan of the key, with its rounded grips;

Fig. 5 is a section thru the center of the axis of the key;

Fig. 6 is a vertical section thru the center of the vertical and horizontal shafts of the assembled machine;

Fig. 7 is a section thru the plane A of Fig. 6, between the cover and the notched disc;

Fig. 8 is a section thru the plane B of the same figure, passing thru the first spring, the first cup and driving sleeve fixed to the notched disc attached to the key-shaft;

Fig. 9 is a section in the plane C, thru the second spring, the second cup and the sleeve fixed to the first cup. This figure, besides the fixed pieces of the preceding figures, also shows the play between the sleeve and the key shaft;

Fig. 10 is a section thru the plane D, the fourth spring, the fourth cup and the sleeve of the third cup;

Fig. 11 is a view of the crown gear from below, with the sleeve removed, showing also the driven transmission elements;

Figs. 12 and 13 show respectively the second and third transmission elements.

Fig. 14 shows the key shaft, the notched disc and the sleeve rigidly attached thereto;

Fig. 15 is a section thru one of the cups 60 with the sleeve attached;

Fig. 16 is a section thru the fifth cup, showing the crowned toothed transmission gear, the sleeve and the method of connection. This sleeve does not, like the others, 65 serve as an attachment for the spring, but as a collar for the crown gear and bearing for the key shaft and the cups;

Fig. 17, is a front elevation of the sleeve.

Fig. 18, is a longitudinal section of the 70 sleeve, and

Fig. 19, is a transverse section of the sleeve.

Referring to the drawings:

The key shaft 1 passes thru the top cap 75 2, which is secured to the top of the cylinder 3. The cylinder is mounted on a base 4, to which is secured the transmission casing 5 by means of screws 5^a. The motor is fixed in place by means of removable base plate 80

6. This plate covers the bottom of the framework and completes the casing. When removed, the works may be inspected and repaired.

Means are provided for utilizing the cylinder of the engine as a container for the motor spring. A plurality of flat spiral springs are used, one above the other and connected in series, all mounted within the cylinder, thereby producing a long-running 90 motor in a form whose exterior resembles a small, one cylinder gasoline engine. The series of springs are mounted each in its cup 8. Fastened to the base of the cups 8 are sleeves 9, turning free on the key shaft 1. 95 These serve as bearings for the cups and as spacers separating the cups and keeping adjacent springs from touching. Moreover, slots 10 in the sleeves 9 serve as points of attachment for the inner ends of the springs 7, the outer ends of which are detachably engaged by tongues 11, punched in the circumference of the cup 8. 12 are slots in the cup thru which the springs can be removed. To simplify the construction the key shaft 1 is 100 stepped in the base plate 6 (Fig. 6) which also serves as a bearing for the sleeve of the crown-gear wheel 13 and for the other cups. The transmission gearing which is constructed to multiply the speed, is ar-

105

110

ranged in a casing to one side of the base of the cylinder, the spring motor shaft and the drive shaft being at right angles, thus producing the external appearance of an engine driving mechanism and its housing.

The crown gear wheel meshes with the pinion 14, mounted on the transmission shaft 15, which turns in a bearing 16 in the transmission casing 5.

- 10 In order to multiply the speed by mechanism occupying but little space, the driven shaft is split into two members and a jack shaft and intermediate gearing are provided. The transmission shaft 15 carries gear 17 which engages the pinion 18 mounted on the jack shaft 19, having its outer bearing in the front of the transmission casing 5 and its inner bearing in the side of the base 4, shaft 19 carrying in addition the gear 20. The gear wheel 20 meshes with pinion 210 attached to the driven shaft 22, which turns in a bearing 23 in the transmission casing 5. The driven shaft 22 is mounted independently of transmission shaft 15, and projects beyond the auxiliary casing. It serves to drive the toy or other device. The removable casing 5 permits ready assembly of the transmission gearing and its repair when desired.
- 30 *Winding mechanism.*—The key plate 22^a with rounded-off grips, to prevent lacerating the hand in case of "back-fire" of the spring, turns the key shaft in the direction indicated by the arrow in Fig. 1. The cap 2 secured to the top of the cylinder by tongues 21, which are bent over the cap, carries downwardly struck tongues 24. These engage the projections 24^a stamped upon the disc 25 carried by the key shaft 1 and prevent backward rotation of the key shaft.

45 The sleeve 9 attached to the first cup is connected by means of its slot 10 with the inner end of the second cup spring, the outer end of which is in turn engaged by the tongue 11. In this manner tension is transmitted from cup to cup until the fifth cup spring is wound up. The crown gear wheel 13 being fixedly attached to the last cup, is under the resultant tension of the battery of springs, and with this resultant tension acts upon the transmission unit enclosed in casing 5 thru pinion 14, gear 17, pinion 18, gear 20, pinion 210 and driven shaft 22.

55 Means are provided simulating starting and stopping mechanism, for starting and stopping the motor. A pivoted lever 26 is provided which for simplicity is shaped like a bell crank, the inner end of which engages and clutches the tooth of pinion 18.

60 Three steps of transmission are shown respectively in Figs. 11, 12 and 13.

65 In Fig. 11 the ratio of the teeth on the

crown wheel 13 to those on pinion 14 is as 50 to 9. In Fig. 12 the second transmission stage shows a ratio of 20 revolutions of pinion 18 for one revolution of the crown-gear wheel 13, and in Fig. 13 the ratio of rotation of the driven shaft to that of the crown gear is shown as 72, i. e. under the gearing ratio shown the driven shaft will make 72 revolutions to one of the crown-gear driving wheel. Any ratio of gearing could, of course, be chosen, but in the preferred arrangement of ratios, the numbers of the teeth in the same pair of wheels has no common divisor, and this accomplishes the important function of minimum and equally distributed wear. The operation of winding the springs, starting and stopping the motor and assembling the parts will be clear from the description and drawings.

70 The principles of this invention, altho especially advantageous for application to small toy motors, are nevertheless not limited to such application.

75 The method of connection in series furnishes an available source of energy in a compact form, the resultant action being the power of the springs less loss by friction, rendering the application of a considerable force at any one desired point an easy matter. It can easily be seen that by the coaction of the battery of springs, each spring in winding being under a slightly greater tension than the one following it in the series, and the reverse being the case on unwinding, a greatly increased operating time, 80 power and uniformity of action must result.

85 The parts of the motor can be easily and quickly assembled or demounted; all are interchangeable, can be struck out of light-metal cheaply and rapidly, and the machine can be removed from its support by unscrewing four screws.

90 What I claim and desire to secure by Letters Patent is:

95 1. A spring actuated motor comprising a key shaft, a plurality of springs arranged in series and centered about said shaft, a disc secured to said shaft, means for preventing backward rotation of said disc, a slotted sleeve attached to said disc, said sleeve surrounding said shaft, a plurality of rotatable cups, one for each spring, the outside of the first spring being secured to its cup and the inside of the first spring being secured to said slotted sleeve, a casing having a cylindrical portion enclosing said springs, said casing provided with bearings for the shaft and a driven shaft at the base of the motor at right angles to the key shaft, said parts resembling in appearance a one cylinder gas engine.

100 2. A spring motor, comprising a key shaft, a plurality of springs journaled on said shaft, a cylindrical casing enclosing the

springs and forming a bearing for the key-shaft, a cap secured to the end of the cylinder and provided with downwardly projecting tongues, in combination with a disc having projections and supporting the top spring, said projections adapted to be engaged by said tongues.

3. In a spring motor the combination of a key shaft, a casing, a cap secured to said 10 casing and provided with downwardly extending tongues, a disc with projections adapted to engage said tongues, a slotted sleeve attached to said disc and rotating therewith, a spring fastened at the inner end 15 to the slotted sleeve, and a cup enclosing the spring and provided with means for holding the outer end of the spring.

4. In a spring motor, a key shaft, a series of cups centered on said shaft, spiral springs 20 enclosed in the cups, sleeves attached to the bottoms of said cups and adapted to engage and tension the spring of each succeeding cup, in combination with a crown gear wheel attached to the last spring cup and provided 25 with a sleeve adapted to form a bearing on the key shaft and a support for the series of cups.

5. A spring motor having in combination, a main casing with a projecting cylindrical 30 portion and a bottom plate, a vertical key shaft mounted in said main casing, a plurality of springs surrounding said key shaft, a gear wheel freely rotatable on the lower end of the key shaft, a pinion engaging 35 therewith, an auxiliary casing, an outer driven shaft at right angles to the key shaft, said outer driven shaft being mounted in

and carried by the auxiliary casing and having a free end projecting thru and outside 40 of said casing adapted to be connected to the device to be driven, and multiplying gearing within the auxiliary casing and between the pinion and the outer driven shaft.

6. In a spring motor, the combination of a key shaft, a spring actuated by the key shaft, a disc provided with means for holding said spring under tension, and a slotted sleeve attached to the base of said disc, said sleeve surrounding said shaft and attached 50 thereto.

7. A spring motor comprising a key shaft, a series of coacting springs centered on said shaft, a main casing having a projecting cylinder resembling a one-cylinder gas engine and provided with top and bottom bearings for the shaft, an auxiliary casing attached to one side of the main casing in combination with a transmission system enclosed by said auxiliary casing said transmission mechanism comprising two shafts in line, the inner one of said shafts being mounted in the main casing and the outer shaft being mounted in the auxiliary casing, a counter-shaft mounted between the walls 60 of the auxiliary and main casings multiplying gearing between the springs, the counter-shaft and the driven shaft and a finger lever mounted on the auxiliary casing having a portion adapted to engage and disengage 65 with a tooth of said transmission system.

In testimony whereof, I have signed my name to this specification.

H. E. BOUCHER.
